SURFACE ATTACHED DIRECT LIGHTING FIXTURE

Viktor Schreckengost, Cleveland, Ohio, assignor to Holophane Company, Inc., New York, N. Y., a corporation of Delaware

Application August 9, 1955, Serial No. 37,393

Term of patent 14 years

(Cl. D48—23)

Fig. 1 is a side elevational view of a surface attached direct lighting fixture showing my new design;

Fig. 2 is a bottom perspective view thereof to a smaller scale; and

Fig. 3 is a side elevational view, to a smaller scale, partly broken away and in section.

According to the present design, the portion above the line A—A of Fig. 1 is opaque; the portion between the line A—A and the line B—B is of crystal glass; the side wall below the line B—B is dense and translucent, and the reentrant bottom is crystal glass.

The essential features of my new design reside in the portion shown in full lines.

I claim:

The ornamental design for a surface attached direct lighting fixture, as shown and described.
